United States Patent Office

Des. 234,137
Patented Jan. 21, 1975

234,137

GUN HOLSTER

Earl J. Clark, 8751 Owensmouth St.,
Canoga Park, Calif. 91304

Filed Sept. 21, 1973, Ser. No. 399,316

Term of patent 14 years

Int. Cl. D3—02

U.S. Cl. D22—13

FIG. 9FIG. 10FIG. 11FIG. 12FIG. 13FIG. 14FIG. 1 is a frontal perspective of a gun holster embodying my design;

FIG. 2 is a rear perspective thereof;

FIG. 3 is a side elevation thereof;

FIG. 4 is a side elevation of the opposite side thereof;

FIG. 5 is a rear view thereof;

FIG. 6 is a front view thereof;

FIG. 7 is a top plan view thereof;

FIG. 8 is a bottom plan view thereof;

FIG. 9 is a side elevation of an alternate embodiment of a gun holster embodying my design;

FIG. 10 is a side elevation of the opposite side thereof;

FIG. 11 is a rear view thereof;

FIG. 12 is a front view thereof;

FIG. 13 is a top plan view thereof; and
FIG. 14 is a bottom plan view thereof.

I claim:

The ornamental design for a gun holster, substantially as shown and described.
